HEATER

Allan E. Krausz, Centralia, Ill.

Filed Dec. 10, 1959, Ser. No. 58,630

Term of patent 7 years

(Cl. D81—19)

Fig 1

The side of the heater opposite that shown in Figures 1 and 3 is conventionally plain, and the rear of the heater is conventionally plain.

I claim:

The ornamental design for a heater, substantially as shown and described.
